PAGE 2

Fig. 3

Fig. 4

Fig. 6

FIG. 1 is a side elevational view of a rug washer or similar article embodying my new design;

FIG. 2 is an elevational view of the side opposite that shown in FIG. 1;

FIG. 3 is a front elevational view thereof;

FIG. 4 is a rear elevational view thereof;

FIG. 5 is a top view thereof; and

FIG. 6 is a bottom view thereof.

I claim:

The ornamental design for a rug washer or similar article, as shown.
